UNITED STATES PATENT OFFICE.

ADRIAN RAIS, WATERBURY, CONNECTICUT, ASSIGNOR TO BROWN & BROTHERS, OF SAME PLACE.

MOLD FOR CASTING SEAMLESS TUBING.

SPECIFICATION forming part of Letters Patent No. 331,820, dated December 8, 1885.

Application filed September 16, 1885. Serial No. 177,224. (No model.)

To all whom it may concern:

Be it known that I, ADRIAN RAIS, a citizen of the United States, residing at Waterbury, in the county of New Haven and State 5 of Connecticut, have invented certain new and useful Improvements in Molds for Casting Seamless Tubing; and I do hereby declare the following to be a full, clear, and exact description of the invention, such as will enable others 10 skilled in the art to which it appertains to make and use the same.

My invention has for its object to devise a mold and core of this class in which the core is necessarily held exactly central, and in 15 which the mold itself is thoroughly protected against the wearing action of the molten metal in the act of pouring.

In order that my invention may be clearly understood, I will describe the same in connection with the accompanying drawings, forming part of this specification, in which—

Figure 1 is a central longitudinal section of the mold complete and ready for use; Fig. 2, an elevation with the receiver removed, and 25 Fig. 3 a plan view of the upper core-bit detached.

A represents the mold, B the base, and C the core, the latter being made in the usual or any suitable manner.

30 An important feature of my improved construction is that the core is made tapering or inclined inward at both ends, as shown at D. The lower end of the core rests in a core-bit, E, which is provided with an opening 35 through it, the upper portion of which is tapered, as at F, to correspond with the taper at the lower end of the core. The lower core-bit ordinarily rests upon a pin, G, driven through holes in the mold.

40 H represents a washer, one or more of which may be interposed, if necessary, between the pin and the core-bit.

K is an aperture at the upper portion of the mold, through which surplus metal passes out 45 should more be poured in than is required to form the tube. Above this aperture the diameter of the mold is enlarged, as at L, to receive the upper core-bit. The construction of this upper core-bit is an important feature 50 of my invention. It consists of an inner sleeve, M, having an aperture through it, the

lower portion of which is tapered downward and outward, as at N, the taper corresponding exactly with the taper at the upper end of the core.

55

O is an outer sleeve whose external diameter just permits it to pass into enlargement L, at the upper portion of the mold. The inner sleeve is supported in the outer sleeve by means of bridges or cross-pieces Q, as 60 clearly shown in Figs. 1 and 3.

In pouring the molten metal, if it comes directly in contact with the interior of the mold the effect is to wear away the metal very rapidly. This difficulty is wholly overcome by 65 means of the sleeve O, whose inner sides are inclined or tapered inward from top to bottom, as shown at P in Fig. 1, so that the molten metal is turned inward against the core instead of coming in contact with the surface 70 of the mold when it is poured in, as formerly.

R is the receiver provided with a sleeve, S, which fits over the exterior of the mold at the top. This receiver is so constructed that, no matter how the metal is poured in, it can 75 only enter the mold through the upper core-bit, and, as stated above, is thrown against the core instead of the surface of the mold.

In use pin G and the lower core-bit are placed in position. If the mold is short, one 80 or more washers may be used. The core is then placed in position, and the upper core-bit passed over the top of the same and allowed to drop into position within enlargement L. It will of course be apparent that 85 the corresponding inclines at the lower end of the core and in the lower core-bit will hold the base of the core firmly in position. The construction is such that the exact length of the core is not essential. The upper core-bit 90 will drop down over the core until the corresponding inclines upon the core and in the core-bit are in engagement. As the external surfaces of sleeve O and enlargement L are perpendicular and parallel with each other, it 95 follows that both long and short cores will be held firmly in position.

Having thus described my invention, I claim—

1. A solid core of uniform diameter, except at its ends, both of which taper inward, in combination with a lower core-bit having an

opening tapered upward and outward to receive the base of the core, and an upper core-bit adapted to move vertically in the mold, and having an opening tapered downward and outward to engage the taper of the core, whereby the latter is held firmly whether long or short.

2. A solid core having reduced tapered portions at both ends, in combination with a core-bit having an opening tapered upward and outward to receive the base of the core, and an upper core-bit consisting of a sleeve adapted to move vertically in the mold, and an inner sleeve connected thereto by cross-pieces, 15 said inner sleeve having an opening tapered downward and outward, to adapt it to slip down upon the incline of the core, whereby the latter is firmly held in all positions.

3. The combination, with the core, of a core-bit consisting of a sleeve having an opening to receive the core, an outer sleeve whose outer sides are straight and whose inner sides are inclined inward from top to bottom, and bridges which connect the two sleeves. 20

25 4. The combination, with a core tapered at its upper end and a correspondingly-tapered

sleeve which engages said core, of the mold, a sleeve fitting within the mold and tapered inward from top to bottom, and bridges extending to the inner sleeve by which the latter is supported. 30

5. The combination, with the mold, the lower core-bit, and the core, of a sleeve which supports the upper end of the core, cross-pieces or bridges Q, and an outer sleeve fitting 35 within the mold and having sides inclined inward from top to bottom, whereby in pouring the metal is thrown against the core, thus protecting the mold.

6. The mold having enlargement L and the core tapered, as shown, in combination with the lower core-bit having a tapered opening, sleeve M, having a tapered opening, and sleeve O, adapted to fit the enlargement of the mold and having incline P, whereby the metal is 45 thrown against the core.

In testimony whereof I affix my signature in presence of two witnesses.

ADRIAN RAIS.
